THREAD-CHAIN CUTTER FOR SEWING MACHINES

Hans Hacklander, Linden, N. J., assignor to The Singer Manufacturing Company, Elizabeth, N. J., a corporation of New Jersey

Application September 16, 1941, Serial No. 410,967

4 Claims. (Cl. 112—252)

This invention relates to improvements in thread-chain cutters for sewing machines of the type wherein the material being stitched is adapted to be supported and fed through the machine by feeding wheels or "cups." Machines of this type are customarily employed for seaming hosiery and the like.

In the seaming of hosiery the sewing machine used for effecting the seam-closing operation is required to be fitted with a thread-chain cutter at the discharge side of the usual feed-cups. In prior machines the custom has been to provide a thread-chain cutter of the type comprising a horizontal plate-member secured at one end to the machine-frame and at its free end provided with a thread-notch sharpened along one side to provide a cutting edge. Such a thread-chain cutter is illustrated in the U. S. patent to J. R. Moffatt, No. 1,150,614, issued Aug. 17, 1915. It will be understood that in a thread-chain cutter of the type shown in the Moffatt patent the plate-member at its free end must not extend across the normal line of seam-formation, otherwise the end of the plate-member would interfere with the feeding of the work through the machine, as well as render it more difficult to properly introduce the work between the feed-cups. Since the free end of the plate-member terminates on the inner feed-cup side of the normal line of seam-formation, the thread-chain cutting notch also is disposed to one side of the normal line of seam-formation. This out-of-line position of the thread-chain cutter results in disadvantages. One of these disadvantages is that the thread-chain cutting notch is of necessity disposed at too great a distance from the point at which the complementary stitch-forming implements cooperate. This results in the formation of a rather long thread-chain which must be cut off in a subsequent hand operation after the stocking is seamed. Another of these disadvantages is that, since the thread-chain cutting notch is positioned on the inner feed-cup side of the normal line of seam-formation, the thread-chain extending from the usual stitch-finger into the thread-chain cutting notch is at an angular relation relative to the normal line of seam-formation. Tension applied to the thread-chain in the severing operation reacts along the thread-chain and tends to bend the delicate free end of the stitch-finger out of its normal position. When the cutting edge of the cutter becomes dull and a stronger pull must be exerted upon the thread-chain to effect cutting thereof the stitch-finger is frequently broken. Repeated replacements of

new for broken stitch-fingers is an expensive practice, inasmuch as each stitch-finger must be carefully machined and highly polished and is therefore expensive to purchase.

Therefore, it is the primary object of the present invention to provide an improved thread-chain cutter designed so that it may be positioned close to the point at which the thread-handling implements cooperate in the formation of stitches.

It is another object of the invention to provide a simple thread-chain cutter which can be successfully operated without permanently bending or breaking the delicate stitch-finger.

The foregoing and other objects and advantages, together with means whereby the same may be carried into effect, will best be understood from the following description of a preferred embodiment thereof illustrated in the accompanying drawing, in which:

Fig. 1 is a fragmentary horizontal sectional view of a cup-feed sewing machine, such as disclosed in my copending patent application Serial No. 296,031, filed Sept. 22, 1939, embodying the improvement.

Fig. 2 is an enlarged fragmentary perspective view of the elements of the machine at and adjacent to the stitching point, showing clearly the relation between the stitch-finger and the thread-chain cutting notch.

Fig. 3 is an enlarged top plan view of the feed-cups, stitch-forming devices, stitch-finger and novel thread-chain cutter, illustrating the manner in which the stitches are formed in the material and about the stitch-finger.

Fig. 4 is a view substantially the same as Fig. 3, showing the thread-chain which is formed at the end of the hosiery seaming operation positioned in the cutting notch.

Fig. 5 is a perspective view of the presser-spring showing the thread-chain cutting notch formed in the supporting lip thereof.

Referring in detail to the drawing, the machine in which one embodiment of the invention is incorporated includes a machine-frame having a standard 1 which supports an inner feed-cup 2 cooperating with an outer feed-cup 3 depending from the machine-frame. The two feed-cups 2 and 3 are positively driven in synchronism and are adapted to support and feed the material being sewn past the stitch-forming devices.

The stitch-forming devices of the machine illustrated comprise a threaded needle 4 carried by an endwise reciprocating needle-bar 5, an oscillatory threaded looper 6, and an oscillatory

spreader 7 attached to one end of a spreader rock-shaft 8. As clearly shown and described in my above mentioned copending application Serial No. 296,031, the needle-bar 5, the looper 6 and the spreader rock-shaft 8 are operatively connected within the machine-frame to an actuating shaft, and are properly timed and actuated to effect the formation of a two-thread over-seam.

As is common in cup-feed machines of the type disclosed, there is provided a stitch-finger (see Figs. 2, 3 and 4) overlying the feed-cups 2 and 3 at the stitching point and about which the stitches are formed and set to minimize distortion of the marginal edges of the material being sewn. The stitch-finger in the accompanying drawings comprises an attenuated substantially conical blade 9 terminating in a shank 10 secured by two screws 11 upon a support 12 disposed within the upturned peripheral flange 2' of the inner feed-cup 2 and sustained by two screws 13 to an angle-bracket 14 fastened by screws 15 to the wall of the standard 1.

In the operation of the machine, the threaded needle 4, after penetrating the marginal edges of the material, shown as M in Fig. 3, is withdrawn and during the initial portion of its withdrawal stroke casts out a needle-thread-loop T_N (Fig. 2) which is entered by the point of the threaded looper 6. The looper, after entering the needle-thread-loop, carries its own thread T_L over the marginal edges of the material N and presents said thread T_L to the spreader 7 which distends the looper-thread-loop for entrance by the needle 4 prior to its next penetration of the fabric. The looper 6 in carrying its thread T_L over the marginal edges of the material M lays the looper-thread over the blade 9 of the stitch-finger and the spreader 7 distends the limb of the looper-thread thus carried over the blade 9 downwardly to a position where the advancing needle 4 enters the looper-thread-loop and then passes through the material N beneath the blade 9 of the stitch-finger. In this manner the stitches are formed about the stitch-finger. In the absence of any material M between the two feed-cups 2 and 3, the stitch-finger serves as a support about which the stitches are formed, thus facilitating the formation of the usual thread-chain. The stitches formed in the material M are set when they are about the blade 9 of the stitch-finger and if the setting action is sufficient to tightly set the stitches they tend to cling slightly to the blade 9 of the stitch-finger. The consequent resistance to the free passage of the material through the machine results in a puckering of the material unless additional means is provided to augment the feeding action of the usual cooperating feed-cups 2 and 3.

To this end, the machine illustrated is fitted with a presser-spring 16 having a work-engaging section 17 adapted to yieldingly press the material into contact with the serrated face of the outer feed-cup 3 rearwardly of the stitching point. The presser-spring cooperates with the driven feed-cup 3 to effect a pull-feed action on the material, which action assists the feed-cups in advancing the material through the machine at a uniform rate. For a more complete disclosure of the presser-spring reference may be had to my copending application Serial No. 368,793, filed Dec. 6, 1940. The free end of the presser-spring 16 is formed with a flat supporting lip 18 bent into a substantially horizontal

position to rest upon the upper edge of the peripheral flange 2' of the inner feed-cup 2, thereby to provide means for maintaining the work-engaging section 17 of the presser-spring in proper elevated position for cooperation with the outer feed-cup 3. Formed in the flat supporting lip 18 and preferably opening into the rear edge thereof is a V-shaped notch 19, the sides of which are sharpened to provide cutting edges against which the thread-chain may be drawn and cut. As clearly shown in Fig. 4, the V-shaped thread-chain cutting notch 19 is disposed in the supporting lip 18 so that when the thread-chain, shown as T_C in Fig. 4, is positioned in the notch for severance the same extends from the stitch-finger to the notch in a line passing through the longitudinal axis of the blade 9 of the stitch-finger. When the thread-chain T_C is in this in-line position with the blade 9 a pull applied to the thread-chain to effect the cutting thereof does not bend the delicate blade 9 of the stitch-finger out of its normal position. Even after the cutting edges of the notch 19 become slightly dull an increased pull on the thread-chain necessarily applied to effect the severing thereof does not in any way affect the stitch-finger.

Another important advantage of the present invention is the close proximity of the thread-chain cutting notch to the stitching point. It has long been the endeavor of the trade to provide hosiery seaming machines with a thread-chain cutter disposed adjacent the stitching point so that the thread-chain may be severed close to the beginning and ending of the seam. It will be obvious from Fig. 4 that by forming the cutting notch 19 in the supporting lip 18 of the presser-spring a thread-chain cutter is provided which is positioned as close to the stitching point as is practical.

In order to facilitate the manual introduction of the thread-chain into the cutting notch 19 one of the sides of the notch is extended, as at 20, beyond the end of the other side of the notch, 45 and the rear edge 21 of the supporting lip 18 is cut at an angle to lead the thread-chain into the cutting notch 19. It will be understood that in introducing the thread-chain into the cutting notch 19, the machine-operator need only lay the thread-chain over the supporting lip 18 and pull the same in a direction downwardly and toward the outer feed-cup 3. In the event the thread-chain does not enter the cutting notch 19 directly but contacts the rear edge 21 of the lip 55 18, the thread-chain readily slides along the rear edge 21 and into the cutting notch 19. When the thread-chain is positioned in the cutting notch 19 a slight pull on the thread-chain will sever the same. When the sharpened edges of the cutting notch become dull the entire presser-spring 60 16 can be taken off the machine by removing one of the securing screws 15 and the edges of the cutting notch resharpened on a suitable grinding wheel or stone.

While I have shown the preferred embodiment of the present invention, it is to be understood that other embodiments of the device may be made without departing from the spirit of the invention as set forth in the appended claims.

Having thus set forth the nature of the invention what I claim herein is:

1. A sewing machine having, in combination, stitch-forming devices, a stitch-finger having an attenuated blade, a pair of circularly moving feed-cups provided with cooperating work-en-

gaging faces for supporting and feeding material past said stitch-forming devices, a member located on the discharge side of the feed-cups for engaging the material and urging it into contact with the work-engaging face of one of said feed-cups and having a thread-chain cutting notch therein arranged so that its effective cutting portion is located in substantial alinement with the axis of said stitch-finger blade, said thread-chain cutting notch having one of its sides projecting beyond the end of the other side to provide means facilitating the introduction of the thread-chain into the cutting notch.

2. A sewing machine having, in combination, stitch-forming devices, a stitch-finger having an attenuated blade, a pair of circularly moving feed-cups provided with cooperating work-engaging faces for supporting and feeding material past said stitch-forming devices, a presser-member operable at the discharge side of the feed-cups for assisting the feed-cups in advancing the material, and thread-chain cutting means provided on said presser-member in close proximity to the stitch-forming devices and having an effective cutting portion disposed in substantial alinement with the axis of said stitch-finger blade.

3. A combination presser-member and thread-chain cutter for use on sewing machines having

- cooperating feed-cups for supporting and advancing the material through the machine, comprising, a body portion, a work-engaging section adapted to press the material into contact with the periphery of one of said feed-cups, and a supporting lip adapted to rest upon the periphery of one of said feed-cups and having formed therein a thread-chain cutting notch provided with a mouth opening into one of the edges of said lip.
- 10 4. A sheet-metal combination presser-member and thread-chain cutter for use on sewing machines provided with cooperating feed-cups having tangentially opposed work-engaging faces for supporting and advancing the material through the machine, comprising, a flexible body portion formed with a work-engaging section disposed substantially parallel to the work-engaging face of one of said feed-cups and adapted to press the material into contact with the work-engaging face of one of said feed-cups, and a supporting lip extending from said body portion adjacent said work-engaging section and adapted to rest upon the periphery of one of said feed-cups, said supporting lip having formed therein a thread-chain cutting notch provided with a mouth opening into one of the edges of said lip.
